Walter, Lillibridge, Washington Cunningham
J. R. Weeks

United States Patent Office.

WASHINGTON CUNNINGHAM, OF OXFORD, NEW YORK.

Letters Patent No. 73,582, dated January 21, 1868.

IMPROVEMENT IN BUTTER-WORKERS.

The Schedule referred to in these Letters Patent and making part of the same.

TO ALL WHOM IT MAY CONCERN:

Be it known that I, WASHINGTON CUNNINGHAM, of Oxford, in the county of Chenango, and State of New York, have invented a new and useful Improvement in Implements or Machines for Working Butter; and I do hereby declare that the following is a full and exact description thereof, reference being had to the accompanying drawings, and to the letters of reference marked thereon, making a part of this specification, like letters representing like parts.

Figure 1 represents a top view looking down from above.

Figure 2, a side elevation.

Figure 3, flanges or side iron in connection with the spring roller C.

Figure 4, section through shaft A.

The nature of my improvement consists, firstly, in the mode in which I construct the shaft A, fig. 1, a sectional view of which is given in fig. 4, and in the particular form of the said shaft or compressor; second, my improvement has reference to the relative arrangement and combination of the different parts of the car with the tray D and movable spring-roller C, the object of which is to cause the shaft or compressor A to rise when the butter is hard, as it is in cold weather; third, my improvement consists in the method of constructing and elongating the side rail E of the tray D, which forms a perfect guide to the carriage F as well as a support to the same, in the manner hereinafter set forth; fourth, the manner of elevating the forward end of the tray D, instead of the rear, as in other patents, the advantage of which will be hereinafter described.

To enable others skilled in the art to make and use my invention, I will proceed to describe its construction and operation.

I construct the shaft or compressor A in the form of a rectangular prism, of a length and width proportional to the size of the tray. On the faces or sides of said shaft I affix four oval ribs, G, a sectional view of which is represented in fig. 4. The said shaft is supported upon bearings in the common manner, and turned by means of the crank H. When the crank is turned, the sharp corners of the compressor cut, and the oval ribs press out the milk. I construct the tray D in any convenient form, and of any available dimensions, and affix upon the sides of the same the extension side rail E, which forms a perfect guide to the carriage F, as well as a firm support to the same, and extends beyond the body of the tray in such a manner as to prevent the carriage F from falling over the end of the said tray when drawn to the rear end thereof, as it invariably does in other workers of a similar nature, thus avoiding much inconvenience to the operator, and avoiding wrenching and straining the worker. The carriage is connected and firmly held to the tray by means of the metallic flange B and spring-roller C. The object of the spring is to allow the shaft A to rise and fall according to the temperature and hardness of the butter. When the butter softens, as it invariably does on being worked, in consequence of the heat generated by friction in working it, the stiffness of the spring will cause the compressor or shaft to descend nearer the bottom of the tray D. Thus the worker adapts itself to differences of temperature, and obviates the serious inconvenience which has been experienced in the use of other workers of a similar nature, which cannot be worked in cool weather, when the butter is hard, except with great inconvenience and the exercise of great strength.

I support the tray upon four common legs. The legs supporting the forward end of the tray are made longer than those supporting the rear end, and thus the forward end of the tray is slightly elevated instead of the rear end, as in other workers. This enables the operator to pull the butter down an inclined plane, which is of course much more convenient.

What I claim as my invention, and desire to secure by Letters Patent, is—

1. The spring-roller C, as herein set forth, which allows the compressor A to rise and fall, for the purpose herein set forth.

2. Extending the side rail E, for the purpose of preventing the carriage F from falling, as herein set forth.

WASHINGTON CUNNINGHAM.
